UNITED STATES PATENT OFFICE.

GEORGE A. BURNHAM, OF SAUGUS, MASSACHUSETTS, ASSIGNOR, BY MESNE ASSIGNMENTS, TO GENERAL ELECTRIC COMPANY, A CORPORATION OF NEW YORK.

REVERSE-CURRENT RELAY.

1,213,835.

Specification of Letters Patent. Patented Jan. 30, 1917.

Application filed January 24, 1913. Serial No. 743,915.

To all whom it may concern:

Be it known that I, GEORGE A. BURNHAM, a citizen of the United States, residing at Saugus, in the county of Essex and State of Massachusetts, have invented an Improvement in Reverse-Current Relays, of which the following is a specification.

The proper operation and in a great measure the continuity of service of electric distribution systems is dependent upon the accuracy and characteristics of the relays forming a part of the protecting apparatus. Heretofore where several transmission lines or feeders have been employed to carry current to and from a common set of bus-bars, reverse-current relays have been employed to disconnect the lines or feeders with which they are associated, said relays adapted to be operated by or upon the reversal of the current or energy in said lines or feeders. Some forms of reverse-current relay involve a differential-coil, and if a short circuit occurs at or near the connections to the relay the potential at that point drops to such a low value that the potential-winding has little or no influence on the operation of the relay and results in an unreliable device. Also, in order to provide a coil which will allow the relay to work satisfactorily on voltages even slightly below normal, the winding must be designed to exert a considerable force at such voltages and still have sufficient radiating surface to prevent excessive heating, yet the relay is usually arranged on a switch-board, and must necessarily be small to occupy but little space. The potential-windings are arranged continuously in the circuit which is an important factor in determining the size of the relay. Furthermore, relays having their potential-windings continuously in the circuits are affected by variations in the power-factor conditions, and are liable to operate on account of low power-factor which is objectionable. Furthermore, the relay is liable to operate on overloads or a short circuit of great value when the current flows in the proper direction.

My invention has for its object the construction of a reverse-current relay whereby these many objections are overcome, and involves the employment of two differential-coils, the windings of one being wound in the same direction, and the windings of the other being wound in opposite directions,

one of the windings of each coil being included in a closed circuit of a current-transformer which is associated with one of the feeder-wires and the other winding of each coil being included in an open transformer circuit of a potential-transformer arranged in shunt with the feeder-wires, and switch-operating means, which is normally biased to open position and adapted to be moved to closed position by or upon reversal of the current in the differential-coils, and upon closure of the open transformer circuit, and a relay-switch or equivalent electro-responsive means for closing said open transformer-circuit, the coil of which is included in or controlled by the closed transformer-circuit.

My invention, however, comprehends the employment of a single differential-coil having one of its windings arranged in an open transformer-circuit, and a relay-switch or equivalent electro-responsive means to control said open circuit, which is responsive to variations in the current value of the closed transformer-circuit.

Figure 1 is a front elevation of the reverse current relay. Fig. 2 is a side elevation. Fig. 3 is a plan view, and Fig. 4 is a diagram of a circuit including the reverse current relay. Fig. 5 is a modified form of relay-switch which may be employed. Fig. 6 is a modified form of reverse current relay which may be employed.

The electric distribution system here shown for the sake of illustrating my invention is a single phase system, but it will be understood that the invention is adapted for any use of the polyphase systems by a simple duplication of the parts. In the system here shown, 10 and 12 represent the bus-bars at the generating station; 13 and 14 the bus-bars at the sub-station; 16, 17 and 18, 19, the feeder-wires connecting said bus-bars. As represented in Figs. 1 to 4, the reverse current relay comprises essentially two differential-coils, said coils each consisting of a current-winding 20 and 21, and a potential-winding 30, and 31, the current-winding and potential-winding of each coil being arranged in the same magnetic-circuit, and on stationary cores 23, 33. Each differential-coil has an armature made as a movable core-piece 24, 34, and said core-pieces are attached to the extremities of a walking-beam 40, pivoted at 41, and bearing the mov-

able contact-member 42 of a switch arranged for engagement with a stationary contact-member 43. Said contact-members 42, 43, are connected in a circuit 44, including the tripping-coil 45, of a switch 46, of any suitable construction, which is arranged in the feeder-wires, and adapted when operated to open the circuit. The current-windings 20, 21, are connected in series relation in a transformer-circuit 50 of a current-transformer 51, the primary of which is connected with one of the feeder wires, and said windings are made alike and are similarly disposed, so that the flow of current through them is in the same direction. The potential-windings are made alike also and are arranged in series in a transformer-circuit 55, of a potential-transformer 56, the primary of which is arranged in multiple between the feeder-wires and is, therefore, shunted, but said potential-windings are wound in opposite directions, so that the current flows through one of them in the same direction that the current flows through its associated current-winding, and flows through the other in the opposite direction to the flow of current through its associated current-winding. The transformer-circuit 55 is normally open, hence the potential-windings are normally inactive, but the current windings are active, and being made alike will exert like pull upon their cores. One of the coils, however, has a longer air gap than the other so that when the strength of one current-winding equals the strength of the other, the tendency is for the walking-beam 40 to rotate counter-clockwise until it strikes the limiting-stop 47, and thereby move the movable switch-member 42 away from the switch-member 43 and open the circuit of the tripping-coil. Thus the switch-operating means is normally biased to open position. Said open transformer-circuit 55 is adapted to be closed as here shown by a relay-switch, the coil 60, of which is included in the transformer-circuit 50, in series relation with the current-windings, and the movable switch-member 61, of which is adapted for movement into and out of engagement with the stationary switch-members 62, 62, which are connected in the transformer-circuit 55, thereby to close said transformer-circuit 55, upon attractive movement of the armature of the coil 60. The coil 60, may be made as a differential-coil as represented in Fig. 5 the two coils being supplied by the series and potential transformers 51, 56, and in such case it would be influenced by a reversal of the current passing through the feeder-wires, but the simple form of coil shown in Fig. 4 is preferred, as it responds to current flowing in either direction and movement of its armature is dependent upon the value of the current.

As long as the current passes through the feeder-wires in the proper direction irrespective of the value of the current the reverse current relay will not operate, that is to say, the parts will remain in the biased position shown in Fig. 4, for the reason that any increase of current in the transformer-circuit 50 will result in a correspondingly increased pull on the walking-beam produced by the current-windings only. Furthermore, if the current is of such value as to cause the relay-switch to operate and close the transformer-circuit 55, momentarily, or as long as a heavy overload or short circuit lasts, the potential-windings being arranged with relation to the current-windings, as shown in Fig. 4, it will be seen that the potential-winding 30, acts to assist the current-winding 20 in holding its core 24, while the potential-winding 31 is so related to the current-winding 21 that it opposes the pull on its core 34, and therefore movement of the same is prevented.

If a short-circuit should occur on the feeders 16, 17, at say 70, current will flow to the short-circuit in two directions, one over the bus-bars 10, 12, feeders 16, 17, passing through that portion of the circuit in the proper direction, and it will also flow from the bus-bars 10, 12, over feeders 18, 19, and bus-bars 13, 14, in the proper direction, and then through the feeders 16, 17, and short-circuit, including the current-transformer 51, in the opposite direction. This will result in a reversal of the flow of current on the current-windings 20, 21, and if the reversal is of such intensity as to cause the relay-switch to close the transformer-circuit 55, then the potential-windings will be rendered active and the potential-windings 31 will assist the current-winding 21, and the potential-winding 30 will oppose the current-winding 20, and as a result the walking-beam will be moved to move the switch-member 42 into engagement with the switch 43, and close the circuit of the tripping-coil and allow said tripping-coil to become energized and operate to open the switch 46. The result is a sudden diminution of the current in the feeders 18, 19. Thus it will be seen that by keeping the circuit of the potential-windings open enables the use of a value of current in the potential-windings which is very much higher than would be the case if said windings were arranged continuously in the circuit, when speaking of potential-windings of given dimensions, and enables the employment of a very much stronger winding. Furthermore, it will be understood that the potential-winding is powerful at very low voltages. In case a time-limit relay is also employed, as here shown, in connection with each set of feeders, it will be observed that when the above described conditions exist the time-limit re-

lay 75, which governs the opening of the switch 76 is started to cause the tripping of the switch, and after a short period of time will trip the switch 76, thus the feeders 16, 17, which are short-circuited will be disconnected from the distribution system and the continuity of the circuit will be maintained over the feeders 18, 19. The reverse current relay which controls the switch 80 will not operate because the current passing through that portion of the circuit is in the normal direction, and the time-limit relay 85, which controls the switch 86 is adjusted for the same time as the relay 75, but the current in said relay 85 is reduced instantly to that value required to supply the translating-devices in the circuit 90, 91, while the time-limit relay 75 has a very high value of current passing through it caused by the short-circuit 70 will move very much faster and cause the switch 76 to trip before the switch 86 is tripped.

Referring to Fig. 6 of the drawing, a single differential-coil is provided, the current-winding 175 being included in a closed transformer-circuit 176, and the potential-winding 177 of which is included in an open transformer-circuit 178. A relay-switch is employed to close the open transformer-circuit, the coil 180 of which is included in the closed transformer-circuit and the switch 181 of which is arranged in the open transformer-circuit. The switch-operating means controlled by the differential-coil consists of a walking-beam 190 pivoted at 191 and bearing a movable switch-member 192 adapted to close upon the stationary switch-member 193 and one end of said walking-beam is connected with the movable core 174 of the differential-coil and the other end thereof has connected with it a dash-pot 194 for retarding its movement in one direction and also has a weight 195 for assisting in moving it in the opposite direction against a limiting-stop 196, and also serve as a current calibration. In this instance substantially the same results are obtained as in the construction illustrated in Figs. 1 to 4. Although as here shown the tripping of the switches is accomplished by a tripping-coil in an open circuit it is obvious that the tripping-coil may be arranged in a closed circuit.

In the above specification and in the following claims I have employed such terms as "current flowing in either direction", "reverse current relay" and "reversal of current" in their commonly accepted sense when alternating currents are considered; namely, as indicative of the direction in which energy flows in the circuit to which the relay is connected.

I claim:

1. A reverse current relay comprising a pair of differential coils, a switch controlled

by said coils, normally biased to the open position and movable to the closed position upon reversal of current, said coils having two windings, one of which is normally inactive and means controlled by the current through the second winding for rendering said first winding active.

2. A reverse current relay having windings arranged in differential relation, a rock-switch governed by said windings normally biased by the relay current to open position and adapted to be moved to closed position upon reversal of the current, one of the windings being included in an open circuit, and means to close said circuit, substantially as described.

3. A reverse current relay having windings arranged in differential relation, a rock-switch governed by said windings normally biased by the current coils of the relay to one position and adapted to be moved to another position upon reversal of the current, one of the windings being normally inactive, and means operated upon an abnormal condition of the circuit to render said winding active, substantially as described.

4. A reverse current relay comprising a pair of differential-coils, a rock-switch controlled by the coils normally biased to one position and adapted to be moved to another position upon reversal of the current, one winding of each of said coils being normally inactive, and means controlled by an abnormal condition of the circuit to render said windings active, substantially as described.

5. A reverse-current relay comprising a pair of differential-coils, a rock-switch upon the arms of which the coils act, normally biased to open position and adapted to be moved to closed position upon reversal of the current, one winding of each of said coils being included in an open circuit, and means to close said circuit, substantially as described.

6. A reverse-current relay comprising a pair of differential-coils, a balanced switch controlled by them, normally biased by the current of the coils to open position and adapted to be moved to closed position upon reversal of the current, one winding of each of said coils being included in an open circuit, and electro-responsive means to close said circuit which is responsive to the current of said coils, substantially as described.

7. A reverse-current relay comprising a pair of differential-coils, a rock-switch controlled by them normally biased by the current coils to open position and adapted to be moved to closed position upon reversal of the current, one winding of each of said coils being included in an open circuit, and a relay-switch for controlling said circuit, the coil of which is included in circuit with the other windings of said coils, substantially as described.

8. A reverse-current relay comprising a pair of differential-coils each having two windings, the windings of one coil being so arranged that under normal conditions current will flow in the same direction in both and the windings of the other coil being so arranged that current will flow in opposite directions in the two windings, switch operating-means controlled by said coils, normally biased to open position and adapted to be moved to closed position upon reversal of the current, one winding of each coil being included in an open circuit, and means to close said circuit, substantially as described.
- 5 9. A reverse-current relay comprising a pair of differential-coils each having two windings, the windings of one coil being so arranged that current will flow in the same direction in both and the windings of the other coil being so arranged that current will flow in opposite directions in the two windings, switch operating-means controlled by said coils, normally biased to open position and adapted to be moved to closed position upon reversal of the current, one winding of each coil being included in an open circuit, and electro-responsive means to close said circuit which is responsive to a current of a predetermined value, substantially as described.
- 10 10. A reverse-current relay comprising a pair of current-windings so arranged that current will flow through both in the same direction and a pair of potential-windings so arranged that current will flow in opposite directions in the two, associated together to form a pair of differential-coils having a preponderant bias on one side, the current-windings being active when the current is flowing in the proper direction and also upon reversal thereof, and the potential-windings being normally inactive and when rendered active adapted to assist one of the current-windings and nullify the other, electro-responsive means to render active said potential-windings and controlling-means for the circuit operated by said coils, substantially as described.
- 15 11. A reverse-current relay comprising a pair of current-windings so arranged that current will flow through both in the same direction and a pair of potential-windings so arranged that current will flow in opposite directions in the two, associated together to form a pair of differential-coils having a preponderant bias on one side, the current-windings being arranged in series relation in a closed transformer-circuit and the potential-windings being arranged in series relation in an open transformer-circuit, electro-responsive means to close said open transformer-circuit, thereby to cause one of the potential-windings to assist its associated current-winding and the other potential-winding to nullify its associated current-
- winding, and switch-operating means operated by said differential-coils, substantially as described.
12. A reverse-current relay comprising a pair of current-windings so arranged that current will flow through both in the same direction and a pair of potential-windings so arranged that current will flow in opposite directions in the two, associated together to form a pair of differential-coils, the current-windings being arranged in series relation in a closed transformer-circuit and the potential-windings being arranged in series relation in an open transformer-circuit, a relay-switch to close the open transformer-circuit, the coil of which is arranged in the closed transformer-circuit, and switch-operating means operated by said differential-coils, substantially as described.
- 15 13. A reverse-current relay consisting of a pair of differential-coils, each coil comprising a current-winding and a potential-winding, the current-windings being alike and so arranged that current will flow through both in the same direction and the potential-windings being alike and so arranged that current will flow in opposite directions in the two, movable cores for said coils, switch-operating means governed by said cores, said cores being biased to remain in position to hold said means with the switch open and movable upon reversal of the current to operate said means to close the switch, a relay-switch, the coil of which is arranged in series with the current-windings and the switch of which is arranged in the circuit of the potential-coils, whereby the potential coils are rendered active upon operation of said relay-switch, substantially as described.
- 20 14. A reverse current relay comprising a pair of differential coils, each having separate current and potential windings, the windings of one being so arranged that current will flow through both in the same direction, and the windings of the other being so arranged that current will flow in opposite directions in the two, a rock switch controlled by them and normally biased by the current coils to open position, the current windings being arranged in series relation in a closed transformer circuit and the potential windings being arranged in series relation in an open transformer circuit, the current winding being active when current is flowing in either direction, and a relay switch responsive to current of a predetermined value in either direction for closing the open transformer circuit, the coil of said relay switch being included in series with the current windings.
- 25 15. A reverse current relay comprising a pair of differential coils each having separate current and potential windings, the windings of one being so arranged that cur-

- rent will flow through both in the same direction and the windings of the other being so arranged that current will flow in opposite directions in the two, switch operating means controlled by them and normally biased by the current windings to open position, the current windings being arranged in series relation in a closed transformer circuit, and the potential windings being arranged in series relation in an open transformer circuit, the current windings being active when current is flowing in either direction and a relay switch responsive to current of a predetermined value in either direction for closing the open transformer circuit, the coils of said relay switch being included in series with the current windings. 10
16. A reverse current relay comprising a pair of differential coils, each coil comprising a current winding and a potential winding, the current windings being alike, and so arranged that current will flow through both in the same direction and the potential windings being alike and so arranged that current will flow in opposite directions in the two, a rock switch controlled by them and normally biased by the current coils to open position, the current windings being arranged in series relation in a closed transformer circuit, and the potential windings being arranged in series relation in an open transformer circuit, the current windings being active when current is flowing in either direction and means controlled by the current through the current windings for closing the open transformer circuit. 20
17. A reverse current relay comprising a pair of differential coils, each coil comprising a current winding and a potential winding, the current windings being alike and so arranged that current will flow through both in the same direction, and the potential windings being alike and so arranged that current will flow in opposite directions in the two, a rock switch controlled by said coils, the current windings being arranged in series relation in a closed transformer circuit and the potential windings being arranged in series relation in an open transformer circuit, the current windings being active when current is flowing in both directions and a relay switch, responsive to current of a predetermined value in either direction for closing the open transformer circuit, the coil of said relay switch being included in series with the current windings. 30
18. A reverse current relay comprising a pair of differential coils, each coil comprising a current winding and a potential winding, the current windings being alike, and so arranged that current will flow through both in the same direction, and the potential windings being alike and so arranged that current will flow in opposite directions in the two, a rock switch controlled by them and normally biased by the current windings to open position, the current windings being arranged in series relation in a closed transformer circuit, and the potential windings being arranged in series relation in an open transformer circuit, the current windings being active when current is flowing in either direction and a relay switch responsive to current of a predetermined value in either direction for closing the open transformer circuit, the coils of said relay switch being included in series with the current windings. 40
19. A reverse current relay comprising a pair of differential coils, each coil comprising a current winding and a potential winding, the current windings being alike and similarly wound and the potential windings being alike and oppositely wound, the current windings being normally active and the potential windings normally inactive, a rock switch controlled by the coils and normally biased by the current coils to open position and means controlled by the current through the current windings for rendering the potential windings active. 50
20. A reverse current relay comprising a pair of current windings so arranged that current will flow through both in the same direction and a pair of potential windings so arranged that current will flow in opposite directions in the two, said windings being associated together to form a pair of differential coils, a rock switch controlled by them and normally biased by the current coils to open position, the current windings being arranged in series relation in a closed transformer circuit and the potential windings being arranged in series relation in an open transformer circuit, and means for closing said open circuit which is responsive to current of a predetermined value in either direction. 60
21. A reverse current relay comprising a pair of differential coils, a balanced switch controlled by said coils and normally biased to the open position by the current in said coils, said coils having two separate windings, one of which is normally connected in a closed transformer circuit and the other of which is normally connected in an open transformer circuit and means controlled by current through the closed circuit and responsive to current of a predetermined value for closing the open transformer circuit. 70
22. A reverse current relay comprising a pair of current windings so arranged that current will flow through both in the same direction and a pair of potential windings so arranged that current will flow in opposite directions in the two, said windings being associated together to form a pair of differential coils, switch operating means controlled by them, and normally biased by the current windings to open position, the current windings being arranged in series relation in a closed transformer circuit, and the potential windings being arranged in series relation in an open transformer circuit. 80

- the potential windings being arranged in series relation in an open transformer circuit, the current windings being active when current is flowing in either direction and a 5 relay switch responsive to current of a predetermined value in either direction for closing the open transformer circuit.
23. A reverse current relay comprising a pair of current windings so arranged that 10 current will flow through both in the same direction and a pair of potential windings so arranged that current will flow in opposite directions in the two, said windings being associated together to form a pair of 15 differential coils having a preponderant bias on one side, the current windings being arranged in series relation in a closed transformer circuit and the potential windings being arranged in series relation in an open 20 transformer circuit, the current windings being active when current is flowing in either direction and means controlled by the current through the current windings for closing the open transformer circuit.
24. A reverse current relay comprising a 25 pair of current windings so arranged that current will flow through both in the same direction and a pair of potential windings so arranged that current will flow in opposite directions in the two, said windings being associated together to form a pair of differential coils, the current windings being arranged in series relation in a closed transformer circuit and the potential windings 30 being arranged in series relation in an open transformer circuit, the current windings being active when current is flowing in either direction, a rock switch controlled by 35 said coils, and a relay switch for closing the open transformer switch, the coil of said 40 relay switch being included in series with the current windings.
25. A reverse current relay comprising a pair of current windings so arranged that 45 current will flow through both in the same direction and a pair of potential windings so arranged that current will flow in opposite directions in the two, said windings being associated together to form a pair of 50 differential coils having a preponderant bias on one side, the current windings being normally active when current is flowing in either direction, and the potential windings normally inactive and means controlled by 55 current through the current windings, and responsive to current of a predetermined value for rendering the potential windings active.
26. A reverse current relay comprising a 60 pair of differential coils having a preponderant bias on one side, said coils having two 65 separate windings, one of which is normally

connected in a closed transformer circuit and the other of which is normally connected in an open transformer circuit and means controlled by current through the closed circuit and responsive to current of a predetermined value for closing the open transformer circuit. 65

27. A reverse current relay comprising a 70 pair of differential coils having a preponderant bias on one side, said coils having two 75 separate windings, one of which is normally active and the other of which is normally inactive and means controlled by current through the active winding and responsive to current of a predetermined value for rendering the other winding active. 75

28. A reverse current relay comprising a 80 pair of differential coils, a balanced switch controlled by said coils, said coils having current windings normally connected in a 85 closed transformer circuit and potential windings normally connected in an open transformer circuit and means controlled by current through the current winding and responsive to current of a predetermined value for closing the open transformer circuit. 85

29. A reverse current relay comprising a 90 pair of similarly wound current windings and a pair of oppositely wound potential windings associated together to form a pair of differential coils, a balanced switch controlled by said coils and normally biased 95 thereby to open position, the current windings being arranged in series relation in a closed transformer circuit and the potential windings being arranged in series relation in an open transformer circuit, and means 100 for automatically closing said open circuit upon the occurrence of abnormal conditions in the circuit to which the relay is connected.

30. A reverse current relay comprising a 105 pair of coils each having two windings, the windings being so arranged that under normal conditions the effect of the two windings in one of the coils is cumulative and in the other coil differential.

31. A reverse current relay comprising a 110 pair of coils, each having two windings, the windings being so arranged that under normal conditions the effect of the windings in the first coil is cumulative and in the second coil differential, and under abnormal conditions the effect in the first coil is differential and in the second coil cumulative. 115

In testimony whereof, I have signed my name to this specification, in the presence of two subscribing witnesses.
